SOUND RECORDING AND REPRODUCING MEANS

Filed June 11, 1929

UNITED STATES PATENT OFFICE

EARLE L. KENT, OF CARTHAGE, MISSOURI

SOUND RECORDING AND REPRODUCING MEANS

Application filed June 11, 1929. Serial No. 370,126.

This invention relates to improvements in sound recording and producing means, and has for its general object to provide a novel form of sound record and novel apparatus for using one or more of said records to produce a desired sound or combination of sounds. The invention is capable of producing practically any sound, but is particularly designed for producing musical tones.

More particularly it is an important object of the invention to provide means for producing musical tones or other sounds without accompanying noise due to operation of the mechanism constituting the invention.

Another important object of the invention is to provide means whereby the tones of a number of different musical instruments, or different sounds, may be produced simultaneously; also to provide means for quickly changing from one combination of tones to another combination of tones, and to provide for imparting a tremolo effect to the tones.

A further important object of the invention is to provide for either manual or automatic operation of the mechanism.

With the additional purpose of providing a mechanism of the character stated which is simple in construction, relatively cheap and easy to produce, which may be compactly assembled, and which is thoroughly reliable and efficient in use, and with various other purposes in view, the invention consists in the novel features of construction, combinations and arrangements of parts as will be hereinafter more fully described, illustrated in the accompanying drawings and defined in the appended claims.

In the drawings; wherein like characters of reference denote corresponding parts in the different views:—

Fig. 1 is a diagrammatic view of mechanism constituting an operative embodiment of the invention;

Fig. 2 is an elevation of a fragment of one of the record disks, illustrating in an exaggerated manner the method of recording sound thereon.

Fig. 3 is a detail view of one of the electric lamp shields; and

Fig. 4 is a detail view illustrating the manner in which a perforated roll may be employed to operate the mechanism.

Referring to the drawings in detail, A designates, generally, a key board, B a set of tone stops, C a set of combination tone stops, D, D a pair of the present tone records, E, E selenium or other photoelectric cells, one associated with each tone record, F an amplifier, and G a loud speaker.

Each key 10 of the keyboard A, and each of the stops B and C, is constructed in any suitable manner, not entering into the present invention, to constitute a normally open electric switch which is closed when the key or the stop is depressed.

The present tone records D preferably are produced in the form of thin disks of celluloid or other suitable material, and the tones are recorded thereon by opaque and transparent strips 11 and 12, respectively, arranged on the disks in narrow, concentric bands transversely of the latter, the width or spacement of the strips of said bands determining the tones of the latter as will hereinafter become more fully apparent.

The cell or cells E may be of any well known type capable of changing light waves or pulsations into electrical waves or pulsations, and likewise the amplifier F and the loud speaker G may be of any suitable type.

The records D are adapted to be rotated, and to this end shafts 13 are provided on which said records may be interchangeably mounted. The shafts 13 may be journaled for rotation in any suitable manner and they are adapted to be driven collectively, at the same rate of speed, in any suitable or desired manner, as, for example, by an electric motor 14 and suitable gearing 15.

Any desired number of record disks having different tone bands thereon may be employed, and as aforesaid, each record disk has individual cells E. In addition, each record disk has adjacent thereto a set of small electric lamps 16 corresponding in number to the number of tone bands on the

disk and disposed, respectively, individual to said tone bands. Preferably each lamp 16 is enclosed by a shield 17 provided with a narrow light emitting slit 18 arranged to 5 permit only a narrow beam of light to be projected from the lamp onto its related tone band.

The lamps 16 of each record disk are disposed to one side of said disk and the cell E 10 of each disk is disposed to the other side thereof in a position to receive light rays passing from any one of said lamps through the transparent strips of its related tone band. Thus, with the record disks being rotated, it is apparent that when any lamp 16 is lighted a series of light waves or pulsations will be projected upon the related cell E, the frequency and the period of said pulsations depending, of course, upon the 15 character of the opaque and transparent strips of the related tone band, and upon the 20 rate of speed at which the record disk is rotated.

A source of current such as an electric 25 battery is indicated at 19. All like contacts, i. e., all of the stationary or all of the movable contacts of the switches (not shown) of the keys 10, are connected in series and with one pole of the source of current 19 by 30 a conductor 20, while from the other switch contact of each key 10 a separate conductor 21 leads to one of the terminals of a related lamp 16 of each set of such lamps. The other terminals of each set of lamps 16 are 35 connected in series, there being a separate conductor 22 for the series connected terminals of each set of lamps. One of these conductors 22 is connected to one of the switch contacts of one of the tone stops B, another is connected to the corresponding 40 switch contact of another of the tone stops B and so on, there being a tone stop B individual to each set of lamps 16. The other switch contacts of the tone stops B are connected in series and with the other pole of 45 the source of current 19 by a conductor 23.

Corresponding switch contacts of the combination tone stops C also are connected in series and with the last mentioned pole 50 of the source of current 19 by the conductor 23. From the other switch contact of each combination tone stop C a separate conductor 24 leads to a set of series connected switch contacts 25.

55 Each switch contact 25 has a complementary contact 26, and from said contacts 26 separate conductors 27 lead to and are connected with the conductors 22, respectively.

60 The cells E are connected in multiple and with the amplifier F by conductors 28, said cells receiving current from the local source of current of the amplifier when a switch 29 in one of the conductors 28 is closed.

65 In view of the foregoing, assuming the

motor 14 to be in operation rotating the record disks D, the operation of the invention as thus far described is apparent and as follows:

If only a single tone is desired, or if a combination of tones, not provided for by the combination stops C, are desired, the proper stop or stops B is or are depressed, thereby including one or more of the conductors 22 in circuit with the conductor 23. 75 If now a key 10 is depressed a circuit will be completed from one pole of the source of current 19 through the conductor 20, the related conductor 21, the related lamp or lamps 16 of one or more sets of said lamps 80 as the case may be, the conductor or conductors 22, the closed switch or switches of the depressed stop or stops B, and the conductor 23 to the other pole of the source of current. Thus, the lamp or lamps related 85 to the depressed key 10 will be illuminated and light rays therefrom will be projected in waves or pulsations, caused by the strips 11 and 12, and the rotation of the record disks, upon one or more of the cells E, the 90 duration of the pulsations depending, of course, upon the length of time the key 10 is held depressed.

The light pulsations received by the cell or cells E are changed by the latter into 95 electrical pulsations, and these electrical pulsations are amplified by the amplifier F, after which they are passed through the loud speaker which produces the sound of the tone or tones in a manner which is well 100 known and which in itself forms no part of the present invention.

Although it is possible as just explained to secure a combination of tones by manipulating the stops B, this is not desirable nor entirely practicable and for this reason the combination stops C and the switches 25 and 26 have been provided. By engaging any desired combination of the contacts 25 and 26 and depressing one or more of the 105 stops C any desired combination of tones

may readily and easily be obtained. Under such conditions the circuit then will be, proceeding for clearness in a direction opposite to the circuit previously traced, from one pole of the battery 19 through the conductor 23 to the closed switch of the depressed stop or stops C, to the conductor or conductors 24, through the closed switch contacts 25 and 26, to the conductors 27 of the closed switch contacts 26, to the lamps 16, to the conductors 21, through the closed contacts of the depressed key 10, and through the conductor 20 to the other pole of the battery. Since the switch contacts of the stops B are normally open the circuit will necessarily be as just recited if the stops B are not depressed.

A rheostat 30 is provided for regulating the speed of the motor 14 to vary the pitch 130

- of the tones produced. In addition, a rheostat 31 is provided for operation by a swell pedal in any suitable manner to control the volume or intensity of the tones produced.
- 5 Furthermore, a small generator 32 preferably is suitably driven by the motor 14 to furnish an alternating current for a coil 33 designed to produce pulsations in the circuit 28 to give the tremolo to the tones produced.
- 10 From the foregoing description it will be apparent that by properly spacing the strips 11 and 12 of bands on the record disks, and by rotating the disks at a proper rate of speed, the music of practically any instrument may be reproduced, and this being true, it follows that by providing a greater or lesser number of record disks band or orchestra music may be produced. In fact the apparatus constituting the invention is 20 capable of producing any sound which is capable of being recorded in the manner stated.
- As an example of the flexibility of the apparatus, a radio receiving set H and a 25 phonograph reproducer I may be included in circuit with the amplifier F through the conductors 28 and either may be used when no musician is present to manipulate the keys 10.
- 30 Furthermore, the apparatus may be designed to produce music by means of a perforated roll such as is used in a player piano. This may be accomplished by providing a plate 34 over which the perforated 35 roll 35 may be caused to travel in any desired manner. The conductor 28 may be connected with this plate and a set of small spring contacts 36 may be provided and mounted in any suitable manner so that the 40 roll 35 travels between them and the plate 34, solid portions of the roll thus serving to break contact between said spring contacts and the plate, and the perforations in the roll allowing said contacts to engage the 45 plate. Thus, by connecting the respective spring contacts 36 with the conductors 21 as indicated at 37, the same result will be had when the roll 35 is moved over the plate 34 as is had when the keys 10 are depressed, 50 the roll merely taking the place of the keys 10 as is manifest.
- If desired, in order to automatically change the stops, assuming all of the latter to be in circuit closing position, a second set 55 of spring contacts 38 may be provided and connected, as indicated at 39, with the conductors 27. Thus, by providing proper perforations in the roll 35 to allow the contacts 38 to engage the plate 34 the same result 60 may be caused to be produced by the roll as is manually produced by finger manipulation of the stops B and C. The perforations for the contacts 38 necessarily will be of considerable length and in order to permit connecting webs to be provided at inter-
- vals across long perforations, the contacts 38 preferably will be made double, as shown, so that at least one of them will be in contact between one of said contacts and the plate.
- 70 From the foregoing description considered in connection with the accompanying drawings, it is believed that the construction, operation and advantages of the invention will be apparent. It is desired to point out, however, that various changes and desirable additions may be made in and to the structure shown within the spirit and scope of the invention as defined in the appended claims.
- 75 I claim:
1. In combination with a movable member having a band composed of opaque and transparent portions, an electric lamp disposed to one side of said member, means disposed to the other side of said member in position to receive light waves projected from said lamp through the transparent portions of said band, and to change said light waves into electrical waves, means for moving said member, means for flashing said lamps, means for changing said electrical waves into sound waves, and means for imparting a tremolo effect to said sound waves.
- 80 2. In combination with a movable member having a band composed of opaque and transparent portions, means for moving said member, an electric lamp disposed to one side of said member, means disposed to the other side of said member in position to receive light waves projected from said lamp through the transparent portions of said band, and to change said light waves into electric waves, means for changing said electrical waves into sound waves, electrical connections between said two last named means, and means for inductively associating an alternating current with said connections whereby a tremolo effect may be imparted to said sound waves.
- 85 3. In testimony whereof I affix my signature.
